UNITED STATES PATENT OFFICE.

JOHN C. O. REDINGTON, OF SYRACUSE, NEW YORK.

BARREL-FORMING MACHINE.

SPECIFICATION forming part of Letters Patent No. 699,237, dated May 6, 1902.

Application filed May 13, 1901. Serial No. 60,029. (No model.)

To all whom it may concern:

Be it known that I, JOHN C. O. REDINGTON, a citizen of the United States, residing at Syracuse, in the county of Onondaga and State of New York, have invented certain new and useful Improvements in Barrel-Forming Machines; and I do declare the following to be a full, clear, and exact description of the invention, such as will enable others skilled in the art to which it appertains to make and use the same.

The invention relates to barrel-forming machines designed especially for forming what are known in the art as "veneer-barrels," which consist of heads, hoops, and sheets of veneer.

The object of the invention is to provide a machine of this character which shall be simple of construction, durable in use, comparatively inexpensive of production, and efficient in operation.

With this and other objects in view the invention consists of certain novel features of construction, combination, and arrangement of parts, which will be hereinafter more fully described, and particularly pointed out in the appended claims.

In the accompanying drawings, Figure 1 is a longitudinal vertical sectional view through the machine. Fig. 2 is a cross-sectional view, and Fig. 3 is an end view.

In the drawings, 1 and 2 denote supporting posts or standards, the latter of which is hinged at 3 to swing downwardly.

35 4 denotes a shaft supported in boxes at the ends of said posts, and 5 denotes a sleeve interiorly screw-threaded to engage the exterior threads of said shaft for longitudinal adjustment thereon.

40 6 denotes the former-cylinder, which consists of longitudinal segmental sections 7, connected together by coiled springs 8 and provided with inwardly-projecting bearing-blocks 9, which are engaged by conical

45 spreader-heads 10, fixed to said sleeve, whereby said sections 6 may be spread apart the desired distance. Any suitable means may be employed for operating this sleeve—such, for instance, as a hand-wheel 11, secured to the

50 end of the sleeve—and any means may be employed for rotating the shaft—such, for instance, as a pivoted foot-lever 12, having a

pawl 13, engaging a ratchet 14, fixed to the shaft.

15 denotes a roller supported at the upper end of spring-arms 16 and pressing against the former-cylinder.

17 denotes grooves cut into the former-cylinder to receive the inner hoops of the barrel.

The inner hoops of the barrel are placed in these grooves, the sections 6 of the cylinder spread apart, the veneer tacked or nailed to the inner hoops, the former being rotated during this tacking or nailing operation by the foot-lever or otherwise. After the barrel 65 has been completed by folding down the post 2 it may be readily removed from the former-cylinder.

From the foregoing description, taken in connection with the accompanying drawings, 70 the construction, mode of operation, and advantages of the invention will be readily understood without requiring a more extended explanation.

Various changes in the form, proportion, 75 and details of construction may be made within the scope of the invention without departing from the spirit or sacrificing any of the advantages thereof.

Having thus described my invention, what 80 I claim, and desire to secure by Letters Patent, is—

1. In a barrel-forming machine, the combination with segmental sections arranged in cylindrical form and provided with inwardly-projecting bearing-blocks, springs connecting the sections of the cylinder and exerting their energy to draw them toward each other, a rotatable screw-shaft, a sleeve loosely mounted upon said screw-shaft and provided with fixed 90 cones, the bases of which project in the same direction and which have a screw-threaded connection with said shaft, and means for rotating the sleeve to move said cones longitudinally upon said shaft to spread the sections 95 of the cylinder, substantially as set forth.

2. In a barrel-forming machine, the combination with segmental sections arranged in cylindrical form, a shaft, bearing-posts for supporting said shaft, said shaft having a 100 separable connection with one of said bearing-posts, bearing-blocks projecting inwardly from the cylinder-sections, a sleeve loosely mounted upon said shaft and provided with

fixed cones adapted to engage the bearing-blocks and spread said sections, one end of said sleeve being provided with a hand-wheel, by means of which the sleeve may be rotated, 5 and springs connecting the cylinder-sections and exerting their energy to draw them toward each other, substantially as set forth.

In testimony whereof I have hereunto set my hand in presence of two subscribing witnesses.

JOHN C. O. REDINGTON.
